UNITED STATES PATENT OFFICE

2,064,879

APPARATUS FOR CARBONATING AND
DISPENSING LIQUID

Wilhelm Bösmann, Berlin, Germany

Application November 27, 1933, Serial No. 700,013
In Germany April 27, 1933

8 Claims. (Cl. 225—21)

The invention relates to an apparatus for the production and retail of liquid, more particularly water, impregnated with gas, such as carbonic acid, with the use of a measuring and a supply vessel and an impregnating device situated between the two.

The known apparatus for carbonating and bottling water or for dispensing the same usually includes flat movable diaphragms or plungers and large size vessels in which the gas is to be taken up by the water. Such apparatus is open to the objections that it is difficult to prevent the accumulation of air in the vessel and at one or both sides of the diaphragm and that the high pressure of the charging gas makes it difficult to supply fresh water to the apparatus.

An object of the invention is to provide simple and efficient apparatus, of small size and low cost, for impregnating liquids with gas, and bottling and/or dispensing the charged liquid. An object is to provide apparatus of the type stated for supplying successive and equal volumes of water to the charging chamber, and simultaneously discharging equal volumes of charged water therefrom. A further object is to provide apparatus for charging liquids with gas from high pressure containers, the apparatus being characterized by a measuring chamber to which successive and equal volumes of liquid are supplied, a gas-charging chamber in communication with the high pressure gas supply, and a discharging chamber from which the charged liquid may be delivered; the three chambers being so associated with a multiple valve that the high pressure in the charging chamber does not affect the free flow of liquid through the three chambers. More particularly, an object is to provide apparatus of the type stated which includes a measuring chamber in the form of a flexible or elastic bag or ball, located in a vessel, the space between the bag or ball and the vessel constituting a discharge chamber which is connected to the measuring chamber through the gas-charging chamber and a system of valves. A further object of the invention is to provide apparatus of the type stated in which the charging chamber has the form of an elongated tube or series of tubes which are filled with small bodies of large total surface area, the gas inlet to the chamber being at the highest point thereof. Further objects are to provide a venting valve system for removing air from the several conduits and chambers of the apparatus, and to provide an outlet system permitting the alternative discharge of the charged liquid into bottles or into glasses and the like.

These and other objects and advantages of the invention will be apparent from the following specification when taken with the accompanying drawings, in which

Fig. 1 is a view, partly in section, taken through the entire apparatus. 5

Fig. 1a is a fragmentary showing of a modification which may be introduced into the apparatus.

Fig. 2 is a section through the three-way delivery valve and measuring apparatus, the section being on a vertical plane normal to that of Fig. 1. 10

Fig. 3 is a plan view omitting the measuring and delivery chambers. 15

Figs. 4 and 5 are schematic sectional views illustrating the two control sections of the delivery valve and their relation to the two sections of the measuring apparatus, the schematic views including sections taken on lines A—A and B—B, respectively, of Fig. 2; Fig. 4 showing the position of the three-way cock in which delivery takes place, and Fig. 5 a displacement of the three-way cock to the extent of 90°, in which position there occurs the impregnation. 20

Fig. 6 is an axial section through the dismantled non-return element. 25

Fig. 7 is a perspective view of the apparatus ready for operation, wherein the jacket has been partially omitted to reveal the internal parts. 30

In the drawings *a* is a container, which acts as measuring and supply or delivery vessel, and is divided by the rubber ball *b* into an outer chamber or delivery chamber *a*¹ and an inner or measuring chamber *b*¹. To facilitate fitting or exchange of the rubber ball *b* the casing *c* of the container *a* is made in two parts, whereby the detachable cap portion is pressed tightly against the fixed container portion by a peripheral steel band *c*' shown in Fig. 2, the ends of which band are anchored by threaded bolts. *d* is a double three-way cock, and serves for actuating the measuring and delivery device. The discharge nozzle *e*, through which the impregnated liquid is poured into a glass or a bottle, is at the outlet end of the discharge pipe *g* which communicates with the delivery chamber *a*¹. *m* is the feed pipe for the fresh liquid, for example water, and communicates with the interior of the rubber ball, i. e., with the measuring chamber *b*¹. 35

f is the feed pipe for the impregnating gas, for example carbonic acid, and opens into the impregnating pipe *e* filled with a large-surface body, for example glass pearls *e*'. The three- 40

45

50

55

way cock *d* is actuated by the lever shown in Fig. 7, and may be moved alternately into the two positions illustrated in that figure, these positions being determined by stops (not shown).

5 In the one position according to Fig. 4 there passes out of the pipe *m* (Fig. 4 at the right), which must be under pressure, fresh liquid from the connection *i* of the feed pipe *m* through the bore *d*¹ of the three-way cock *d* into the hollow 10 rubber ball *b*, this liquid filling the measuring chamber *b*¹. Since at the same moment the delivery chamber *a*¹ is connected by the bore *d*² of the three-way cock with the discharge pipe *g* (Fig. 4 at the left), there prevails in this chamber 15 merely ordinary atmospheric pressure, and the pressure in the pipe *m* is able to act in the ball *b*. For the purpose in question the rubber ball possesses a thickness of wall amounting to 3-4 mm., and accordingly the pressure of the 20 liquid causes the ball to be expanded until it thrusts against the wall of the container *a*. In this manner the contents of the delivery chamber *a*¹ are expelled into the discharge pipe *g*.

If the cock is now moved into the other position according to Fig. 5, the feed pipe *i* and the 25 discharge pipe *g* will be closed, and the delivery chamber *a*¹ made to communicate with the measuring chamber *b*¹ through the medium of the cock bore *d*², the connections *h* and *k*, the cock bore *d*¹ and the impregnating tube *e*. The impregnating tube is under the pressure of the 30 impregnating gas, and the latter may be as desired.

By reason of the connection established a compensation of pressure is obtained on either side 35 of the rubber ball, and the elasticity of the rubber causes the ball to contract and expel the fresh liquid contained in the measuring chamber *b*¹ through the impregnating tube into the 40 delivery chamber *a*¹. Since the pipe *f* for the gas opens out into the impregnating pipe, the fresh liquid carries the gas with it and assimilates the same. The large-surface body *e*' accelerates the fine distribution and the mixing 45 of gas and liquid. Since the quantity of fresh liquid is always equal to the quantity of impregnated liquid, a dead space filled with gas is unable to form in the measuring or the delivery chamber.

50 By regulating the supply of fresh liquid the impregnated liquid may be allowed to run into open receptacles without appreciable friction, pressure and speed. The impregnated liquid, however, may also be filled directly into bottles, 55 in which connection, as shown, there is the considerable advantage that the liquid flowing out is merely under the pressure of the liquid flowing in (for example, the normal pressure of water in the tap), and at no time under the very 60 much higher pressure of the impregnation container, so that special safety means against bursting of the bottles are unnecessary.

In Fig. 1 *n* is a rib provided on the outer face of the rubber ball *b*, which rib, when the ball expands and thrusts against the inner wall of the container *a*, provides a free passage for the liquid.

The pipe *g* which connects the three-way cock *d* and the discharge nozzle *o* is provided with a rapidly closing double-seated valve, the spindle *p* of which carries at the outer end the hand-wheel *u* and at the inner end the packing *s* which, when the spindle is screwed in, seals off the discharge pipe *o* against the three-way cock. The spindle is passed through the spindle guide *r*', against which the same is sealed

off by the packing *t* also located on the spindle when the packing *s* is opened. *q* is a conical elastic mouth-piece, which is surrounded by a guard bell and is capable of being screwed on to the delivery pipe *o*, and if the filling takes place 5 into bottles serves for introduction into the necks of the bottles.

In Fig. 2 there is shown the three-way cock in axial section. The plug is designated *d*, and possesses two angular bores *d*¹ and *d*². The 10 spaces in front of and behind the plug within the cock casing are designated *y* and *z*. These two spaces communicate with each other through the by-pass *x*, so that a one-sided pressure is 15 unable to take place on the plug as a result of leaky pipes.

As also shown by Fig. 2, the spindle *d*' projecting out of the casing towards the right is sealed off against the casing by a rubber washer 12 which, by means of the coil spring 13, is 20 pressed with its conical sealing face against the likewise conical inner face of the threaded cap surrounding the spindle. In this manner, as shown, there is also obtained relief of the plug against axial thrust.

25 In Fig. 1a there is shown a reservoir *a*² which may be disposed between the impregnating tube *e* and inlet socket *k* by means of pipes *a*³ and *a*⁴.

The impregnated liquid does not in this case 30 pass out of the impregnating pipe *e* into the delivery chamber *a*¹ directly, but first flows into the intermediate container *a*², where it is held in reserve and at the same time may also be clarified.

35 In Fig. 1 there is also provided in the feed pipe *m* for the fresh liquid a non-return element *m*', the construction of which is illustrated diagrammatically in Fig. 6, the single parts being taken apart in the axial direction.

The non-return means according to Fig. 6 consists of a flat rubber diaphragm *5*, which is tightly held about its circular periphery between the likewise circular edges of two metallic cups *1* and *3* forming a casing. Each cup possesses a central bore and an outwardly extending socket *2* or *4*. 40 The rubber diaphragm is also perforated at the centre, and carries a rubber socket *6*, which extends with slight clearance into the casing socket *2*. In this rubber socket *6* there is also fitted a valve, which consists of a perforated metallic sleeve *7*, which is surrounded by a wire net, and the end of which is directed towards the rubber diaphragm is open, whilst the opposite end is closed and preferably possesses an outwardly disposed annular beading *8*, against which the rubber socket *6* can tightly engage. The casing portion carrying the socket *2* is bored at a point 45 opposite the flat rubber diaphragm, whilst the casing portion *3* carrying the inlet socket possesses in the interior an annular groove *10* for 50 the reception of one or more flat metal screens *9*, against which the flat rubber diaphragm rests.

55 In normal operation the liquid passes through the inlet socket *4* and the screen *9* into the casing and the valve sleeve *7*, proceeding between this and the rubber socket *6* surrounding the same to the outlet *2*. The drop in pressure thus produced causes the rubber diaphragm *5* to move against the casing portion carrying the outlet socket *2*, so that the bore *11* is closed.

60 If on account of any kind of disturbance the impregnating gas should attempt to enter the feed pipe for the liquid, the rubber socket *6* will be pressed firmly against the valve sleeve *7*, so that the return flow is blocked. At the same time 65

the rubber diaphragm will be lifted from the bore 11 in the casing and pressed against the screen 9, so that the excess of pressure is able to escape through this bore into atmosphere, which at the same time constitutes a visible indication of the existing disturbance.

In Fig. 4 there is shown on the left hand side the ventilating valve *v* on the plug of the cock, which valve may be closed by hand by means of a threaded cap *w*. This ventilating valve *v* communicates with the outlet connection *h* of the impregnating tube *e* through the medium of the quarter annular groove *d*³ in the plug, this communication taking place when the impregnating tube is disconnected from the measuring and delivery container. In this manner it is possible to perform ventilation with regard to any air which may have accumulated in the impregnating pipe, prior to moving the three-way cock into the position shown in Fig. 5.

The operation of the apparatus is as follows: When the valve *d* is turned to the position indicated in Fig. 4, the measuring chamber *b*' communicates with the fresh water inlet pipe *i* and water, under tap pressure, flows into and fills the ball *b*. This expansion of the ball takes place freely since the discharge chamber *a*' is in free communication with the outlet pipe *g* through valve port *d*². The valve *d* is then adjusted to its other position, thus placing the valve ports *d*¹ *d*² in the positions shown in Fig. 5, i. e., placing chambers *a*¹, *b*¹ in communication through the carbonating conduit *e*. Although conduit *e* is under the high pressure of the charging gas which enters through pipe *f*, this pressure is established at both sides of the rubber ball *b*, and therefore does not prevent a collapse of the ball, which collapse effects a transfer of the measured quantity of water from the ball chamber *b*' to the outer chamber *a*¹. The water is carbonated as it passes through the conduit *e*, and will be discharged from chamber *a*¹ upon the return of valve *d* to the position shown in Fig. 4. Since both chambers are subjected to the high gas pressure in the Fig. 5 position, it is apparent that there can be no differential pressure which will prevent the filling of the ball chamber *b*¹ when the valve is returned to the Fig. 4 position. The only requirement for operation is that the fresh water be supplied to ball *b*, through pipes *m*, *i* and valve port *d*¹ under sufficient pressure to overcome the resiliency of ball *b* and the frictional resistance offered by the pipes and conduits. The "pumping" action of the elastic ball *b* may be obtained by water pressures which are substantially lower than the pressure of the charging gas which enters at pipe *f*. In general, the normal pressure of the city water supply system is adequate for efficient and rapid operation.

What I claim as new and desire to secure by Letters Patent is:

1. An apparatus for producing liquid, more particularly water, impregnated with gas, more particularly carbonic acid, comprising a measuring and delivery vessel, an impregnating device, a rubber ball in the said measuring and delivery vessel dividing the said vessel into two separate chambers, and ribs on the outer face of the said ball disposed in the direction towards the

opening of the delivery chamber of the said vessel.

2. Apparatus for producing liquid charged with gas comprising a rigid vessel, an elastic diaphragm within said vessel dividing the vessel into a measuring chamber and a delivery chamber, and a conduit connecting said measuring and delivery chambers, said connecting conduit including a gas charging chamber.

3. Apparatus for producing liquid charged with gas comprising a rigid vessel, an elastic diaphragm within said vessel dividing the vessel into a measuring chamber and a delivery chamber, inlet conduit means adapted to connect the measuring chamber to a source of liquid to be carbonated, delivery conduit means opening from the delivery chamber, and a conduit connecting said measuring and delivery chambers, said connecting conduit including a gas charging chamber.

4. Apparatus for producing liquid charged with gas comprising a rigid vessel, an elastic diaphragm within said vessel dividing the vessel into a measuring chamber and a delivery chamber, inlet conduit means adapted to connect the measuring chamber to a source of liquid to be carbonated, delivery conduit means opening from the delivery chamber, a conduit connecting said measuring and delivery chambers, said connecting conduit including a gas charging chamber and valve means adapted to close said inlet and delivery conduits while opening both the measuring chamber and the delivery chamber to the connecting conduit and to open said inlet and outlet conduits while closing both the measuring chamber and the delivery chamber to the connecting conduit.

5. Apparatus for producing liquid charged with gas comprising a rigid vessel, a rubber ball within said vessel, inlet conduit means adapted to connect the rubber ball to a source of liquid to be carbonated, delivery conduit means opening from the vessel, and a conduit connecting said rubber ball and said vessel, said connecting conduit including a gas charging chamber.

6. Apparatus for producing liquid charged with gas comprising a rigid vessel including a detachable transparent portion, a rubber ball within said vessel, inlet conduit means adapted to connect the rubber ball to a source of liquid to be carbonated, delivery conduit means opening from the vessel, and a conduit connecting said rubber ball and said vessel, said connecting conduit including a gas charging chamber.

7. Apparatus for producing liquid charged with gas comprising a rigid vessel, an elastic diaphragm within said vessel dividing the vessel into a measuring chamber and a delivery chamber, a conduit connecting said measuring and delivery chambers, said connecting conduit including a gas charging chamber and means for connecting said charging chamber to a source of gas.

8. Apparatus for producing liquid charged with gas comprising a rigid vessel, an elastic diaphragm within said vessel dividing the vessel into a measuring chamber and a delivery chamber, and a conduit connecting said measuring and delivery chambers, said connecting conduit including a gas charging chamber filled with bodies presenting a large surface.

WILHELM BÖSMANN.
